UNITED STATES PATENT OFFICE.

GEORGE HOLT FRASER, OF BROOKLYN, NEW YORK.

PULVERIZING MILL.

Application filed March 20, 1917, Serial No. 156,175. Renewed December 15, 1922.

To all whom it may concern:

Be it known that I, GEORGE HOLT FRASER, a citizen of the United States, residing at No. 226 Quincy Street, in the borough of Brooklyn, county of Kings, city and State of New York, United States of America, manufacturer, have invented certain new and useful Improvements in Pulverizing Mills, of which the following is a specification.

This invention relates to machines for crushing, grinding or pulverizing, and particularly to such machines having a ring having an internal crushing face and internal crushing rolls which are pressed outwardly to crush the material against the inner face of the ring.

In such machines the rolls are movably mounted and the ring or one of the rolls is driven, the other crushing parts being revolved by traction. If the ring is the driving part it may be mounted on a fixed axis, and if one of the rolls is the driving part it may yieldingly support the ring loosely.

My present invention aims to provide improvements applicable to pulverizers of the ring and roller type generally and especially applicable to those in which the ring revolves in a vertical plane.

To this end my present invention provides various improved features and combinations which in their preferred form as applied to a vertical ring pulverizer will be hereinafter more fully set forth with reference to the accompanying drawings, in which—

Fig. 1 is a front elevation showing a loose ring pulverizer with the preferred form of my improvements, the view being partly broken away to show the feed hopper in section approximately on the planes of the lines 1—1 of Fig. 2;

Fig. 2 is a side elevation thereof partly broken away approximately on the planes of the lines 2—2 of Fig. 1 to show the feed hopper in section;

Fig. 3 is a reverse side elevation thereof;

Fig. 4 is a vertical axial section thereof cut on the line 4—4 of Fig. 3 and looking in the direction of the arrow; and

Figs. 5, 6, 7, 8, 9 and 10 are views of a modification showing part of my improve-

ments applied to a pulverizer, and illustrating how I prefer to pivot the swinging bearings when the fixed axes on which they positively swing are located outside of the ring and the springs are outside of the casting.

Fig. 11 is a side elevation partly in vertical section on the line 11—11 of Fig. 12 showing the preferred form of my improved skeleton frame or support, and

Fig. 12 is an end elevation thereof partly in vertical section on the plane of the line 12—12 in Fig. 11.

Referring to the drawings A is the casing, B is the frame or base, C G are the sides or covers, D is the top bearing, E E are the lower bearings, F are the feed spouts, G is the feed hopper, H is the discharge outlet, a are the crushing rolls, b is the crushing ring, c are the roll shafts, d are the pressure springs, and e are the pressure screws of a pulverizer.

These parts may be of any suitable construction for any usual type of ring and roller pulverizer those shown comprising a casing affording a crushing chamber f for the ring and rolls, and a frame or support for these parts. The ring shown is supported loosely on and driven by the top roll which is revolved by its pulley g, and the lower rolls are driven by traction from the ring. The inner face of the ring is concave and the peripheries of the rolls are convex, and the material to be crushed falls through the legs of the hopper G and descends through the spouts F on each side of the ring and flows on to its inner face where it is held by centrifugal force and carried successively past the rolls which crush it until it is fine enough to discharge over the sides of the ring and into the chamber f and fall to the outlet H. Pressure of the springs is adjusted by the screws until it is sufficient to overcome the crushing force of the material on the ring and these springs yield to prevent breakage, and the roll bearings move to equalize the crushing pressure between the rolls and to adapt themselves to the thickness of the material on the ring. An automatic lock h holds the screws e when adjusted, a shut off gate i is provided for start-

ing and stopping the feed, and an adjusting gate *j* regulates the feed. The casing has a side aperture *k* through which the ring passes and shaft slots *l* for permitting radial movement of the roll shafts.

According to the preferred form of my invention shown I provide a two duct feed controlling hopper *I* above the feed gate, a feed divider *J* below this gate, an adjustable chute *K* within the ring, movable or adjustable cheek pieces *L* at the sides of the ring, an improved casing, an improved frame or support, improved roll carriers, improved dust guards, improved rolls, improved pressure means, improved aligning means, and various other features of improvement which I will now describe in detail as applied to a loose ring pulverizer.

Pulverizers of this general character discharge coarse and fine material and a sieve is used to separate the fine from the coarse and return the coarse to the pulverizer with fresh feed, and it is desirable that this returning coarse material should be pulverized as fast as it is returned so that fresh feed shall only be admitted after this coarse material is all pulverized.

My invention provides the two way hopper *I* for controlling character of feed. This is preferably mounted movably, removably or reversibly on the hopper *G*, and has a vertical conduit *R* having a top inlet *S* and a bottom outlet *T* fitting into the mouth or regulating chamber *U* of the hopper *G*, which vertical conduit receives the coarse material returned from the sieve or separator and delivers it in a vertical column or path to the chamber *U* of the hopper. The hopper *I* has one or more side inlets *V* and a fresh feed chamber or conduit *W* communicating with the side inlets so that fresh feed must enter the vertical conduit laterally of the descending column of returned material therein the weight of which will automatically prevent inflow of fresh feed when the conduit *R* is full of returned material, thus insuring that returned material shall be ground in precedence to fresh material so long as there is sufficient returned material to prevent ingress of fresh material, and that fresh material ingress shall be controlled by the presence of returned material. As shown the hopper *I* may be turned in any of four positions to dispose the fresh feed chamber *W* where convenient, and the hopper *I* fits removably in the hopper *G* for this purpose instead of being formed integrally therewith.

Preferably I provide with or following the hopper *I* and between the regulating gate *j* and the feed spouts a movable or adjustable divider *J* for dividing the descending feed and apportioning it between the two sides of the ring so that it can flow on to the inner face of the ring at each side in suitable

proportions to hold the ring in position axially or to compensate for its unequal wear so that it will run true centrally of the chamber *f* if the divider is adjusted to effect this. Any means movable transversely of the adjusting gate *j* may be used to divide the material but I prefer to hinge the vertical divider *J* above the bifurcated legs of the hopper *G* so that its upper edge can be swung under the gate to cut the stream of material as desired for each leg and to adjust this damper by a spring operated handle *m* engaging the teeth of a rack *n* and held therein by a spring *o*. Preferably a shelf *p* is provided above the damper for spreading the descending material. By properly regulating the damper, undue axial stress or movement of the ring or rolls may be obviated, and these parts can be approximately maintained in true positions. I preferably also provide a movable or adjustable chute *K* for adjusting the delivery of material on to the inner face of the ring which preferably slides axially of the ring on feet *q* held on supports *r*, and which has wide sides *s* projecting in pockets *t* in the spouts *F* to receive material descending through the latter. The chute has a high back *u* and a contracted central mouth *v* which discharges the material centrally or at either side of the ring according to the adjustment of the chute. Preferably the chute is automatically adjusted from the ring by levers *w* hinged from pivots *x* and having upper ends *y* struck by the ring when it moves excessively to one side and lower ends *z* carrying the chute and moving it reversely of the movement of the ring to cause the chute to feed material to one side or the other of the center of the ring in opposition to the axial movement of the ring for the purpose of resisting or correcting this.

Preferably I also provide movable and removable sectional passive cheek pieces *L* at each side of the ring for limiting flow of material therefrom and preventing its contact with the casing. As shown these each have a lug or projection *X* resting on a ledge *Y* and are adjustably connected by a bolt *Z* so that they are passive relatively to but can slide axially of the ring to adapt themselves to the position it assumes and can be adjusted to regulate fineness of discharge or take up wear. The bolts *Z* extend from one to the other side of the ring to connect their cheek pieces, and may be at its outside when the ring is loose, but should be inside when the ring is the driving part.

The side or cover *C* preferably has a roll hole *M* opposite each roll and large enough to pass the adjacent roll through it and each roll hole is preferably closed by a roll cover *N* having a shaft slot *l* which is closed by a rocking dust guard *O* (see Fig. 5) which has a semi-cylindrical projection mounted

- slidably in the bored inner end of the bearing to carry the weight of the dust guard from the bearing and cause it to swing with the bearing while it is held against the cover 5 N to close its shaft slot. Each dust guard has a clearance hole around the shaft, and between each bearing and dust guard are two sliding washers P held apart by springs and supported on a revolving collar Q slid- 10 ily mounted and feathered on the shaft to prevent leakage of dust along the shaft or of oil from the bearing. The shaft sustains the sliding washers which work in slide-ways or sockets in the rocking dust guards 15 so that they cannot revolve but are free to slide and prevent leakage as the shaft wears into the bearing metal bushing. The side or cover C¹ is preferably of less diameter than the inner diameter of the ring, so that the 20 ring can be removed over it through the ring aperture k, which is preferably an annular space through which the ring can be removed when the adjacent removable annular wall a¹ of the casing is withdrawn, thus per- 25 mitting removal of the ring without remov- 30 ing the rolls or their bearings at one side, while the side or cover C is larger than the ring and carries the roll covers N which permit the removal of any roll through that side without removing the ring or other rolls.
- According to the preferred form of my invention I support the roll carriers swing- 35 ily from pivotal axes disposed inwardly of the inner face of the ring, and I suspend the lower roll carriers directly on and swing 40 them positively from fixed axes above their rolls and preferably nearly over their center of gravity and I dispose these parts sufficiently inwardly so that the ring can be 45 passed over them without removing them and so that the lower rolls will move approxi- 50 mately horizontally. As shown the upper carrier D is keyed on a shaft b¹ and each roll carrier E is keyed on a shaft c¹ 55 extending through the ring and connecting the carriers at each side of the rolls, and these shafts are inwardly of the spouts F.
- According to another feature of improve- 60 ment I preferably support the parts inde- 65 pendently of the casing by a skeleton frame or support A¹, preferably formed as a sepa- 70 rate removable piece mounted on the base B and having a supporting side d¹ extending from the base upwardly at one side of the 75 ring, an overhanging side e¹ at the other side of and of less size than the inner diameter of the ring, and tubular connections f¹ between these parts for sustaining these spaced sides, which connections have at op- 80 posite sides of the die, and inwardly of its inner periphery, sustaining, guiding or sup- 85 porting, positioning provisions for position- 90 ing the non-rotative carriers for the rolls, which as shown serve as bearings for the piv- 95 otal shafts of the carriers. The frame is 100
- constructed with recesses or apertures opposite the rolls, those in the side d¹ being larger than the rolls so that these can be removed therethrough. The frame has spaced legs g¹ connected by a lower side wall h¹ on its 105 supporting side, and has cross-bars i¹ and cross ends j¹, connected at its other side by a recessed side wall k¹ the upper edge of which is sufficiently spaced apart from the small side or cover C¹ to afford clearance for the 110 lower part of the ring, which is removed by sliding it out through this space. The end walls j¹ are inclined and serve as chutes for the ground material, and afford between them and the side walls passage to the discharge 115 outlet H. The weight of the crushing parts is carried by the frame A¹ which sustains all the other parts of the pulverizer except the outer casing.
- According to another feature of improve- 120 ment the sides C and C¹ are separate and removable instead of being formed integrally with the frame, and are mounted thereon so that they can be renewed if broken as 125 these sides and the cheek pieces and outer casing are subject to wear. Preferably the sides are recessed to bring the dust guards close to the rolls and afford sufficient bearing width without unduly widening the machine, and the side C has a lower recess in 130 notch m¹ coinciding with a smaller recess or notch l¹ in the frame which together afford a manhole closed by a cover n¹ and large enough to give access below the ring as well as within it.
- The casing A preferably comprises a sec- 135 tional sheet metal peripheral part o¹ having an arc-shaped side wall p¹ fitting the edge of the cover C on one side and on the other side the casing is closed by the annular cover a¹ 140 fitting the edge of the cover C¹. Any section o¹ can be removed to remove the corresponding cheek piece section. A wear piece q¹ attached to each lower section o¹ extends 145 to the outlet H.
- According to the preferred form of my 150 improvements the crushing springs are dis- 155 posed inwardly of the roll shafts and intermediate of their carriers and act outwardly toward these and react from one to another so that the pressure of each roll is trans- 160 mitted to and divided between the others and all the crushing pressure is consumed between the ring and rolls so that none is lost in the bearings or pivotal supports. As 165 shown the pressure springs d are three di- 170 vergently acting compression members each extending from the carrier inwardly to an intermediate member B¹, which is prefer- 175 ably free to move to equalize its position be- 180 tween the springs so that the pressure on each roll will be the same. The member B¹ is preferably pivotally or rockingly con- 185 nected to the springs and the springs are 190 preferably similarly connected to their bear-

ings respectively so that they can adapt themselves to the varying movements of the latter.

According to another feature of improvement the crushing springs are collapsible to adjust their pressure or permit the rolls to be moved inward away from the ring, and are adjustable from the maximum pressure position at right angles to the axis of the rolls to an inclined position sufficient to free the rolls from the ring. Preferably the member B¹ is a nut and the screw e engages it to adjust the springs, and the latter are each individually adjustable by screws r¹.

15 Preferably the crushing springs are duplicated at each side of the ring, and I prefer to insure equalizing of pressure at each side by connecting these springs together by the screws e and operating the springs at a slight 20 opposite inclination so that the screw can move to equalize the pressure on each side. For a loose ring mill the springs may collapse outwardly and the connecting screw be a tension member, but for a driven ring 25 mill it is more economical of space to incline the springs inwardly and make the screw a compression member.

My invention provides a lock or knuckle jointed provision or stop s¹ for preventing 30 the spring from buckling past the dead center while permitting them to move in the other direction.

This arrangement permits the springs to adapt themselves to difference in wear of the 35 rolls or to variations in thickness of material, or to imperfections in adjustment, and insures an equilibrium of condition at each side of the rolls.

To support the parts when applied to a 40 loose ring pulverizer my invention provides yielding supports for the top roll adapted to carry the weight of the ring, rolls and their bearings and springs. This is preferably a spring D¹ below the upper roll and 45 sustaining the latter through rocking levers E¹ and rods F¹, which are adjustable by screws G¹ to raise the top roll to provide for wear, or to lower it to permit its removal.

In a loose ring mill it is important that 50 the bearings of the top roll especially should be preserved in parallelism, and my invention preferably provides an equalizer for this purpose which may be any parallel motion device, but is preferably provided by 55 inter-engaging arms H¹ on the rocking supporting levers E¹ which mesh so that they must move together as the top bearings rise and fall with adjustment or under the action 60 of the spring D¹, and compel these bearings to move uniformly.

In operation the return feed controls inlet to fresh feed, the divider apportions the feed at each side of the ring, the distributing chute positions it on the ring, the driven 65 top roll revolves the ring and that revolves

the lower rolls, the feed is crushed by these rolls which swing on their pivotal mountings against the pressure of the intermediate springs. These springs float or move to equalize the pressure on each side of the 70 rolls, and are adjusted to vary the pressure and to provide for wear. The springs are collapsed to remove the ring or any roll, and are individually adjusted to act uniformly. The removable sides will be renewed when 75 worn, the cheek pieces will be replaced by removing the outer casing, and the feed hopper will be turned to conveniently dispose its double conduits.

It will be seen that this invention provides improvements which can be readily and advantageously availed of in whole or in part in connection with pulverizers of the various types, and it will be understood that the invention is not limited to the particular 80 details of construction, arrangement, combination of parts or use set forth as illustrating its preferred embodiment since it can be employed in whole or in part according to such modifications of these as circumstances or the judgment of those skilled in the art may dictate without departing from the spirit of the invention.

One such modification is shown in Figs. 95 5 to 10 inclusive, in which the corresponding parts have corresponding reference letters. In this construction the fixed axes are outside of the ring, and the feed chutes are inwardly of the axes, and pressure springs are used outside of the casing.

According to my invention the roll a 100 comprises a recessed hub u¹ and a shell v¹ having inward projections entering the recesses for fastening it on the hub.

What is claimed is:

1. In combination, an annular crushing die revolving in an approximately vertical plane and having an internal crushing face, a rotatable crushing roll within and eccentric of said die and having a peripheral crushing face reciprocal to the inner face of said die, means for revolving one of said parts, means for supporting said parts, non-rotative movable means at each side of said roll on which said roll is rotatably mounted, 110 and movable aligning means extending through said die for maintaining alignment of said non-rotative means.

2. In combination, an annular crushing die revolving in an approximately vertical 120 plane and having an internal crushing face, a movable and rotatable crushing roll within and eccentric of said die, and having a peripheral crushing face reciprocal to the inner face of said die, means for revolving one of said parts, means for supporting said parts, movable non-rotative members at each side of said roll and on which said roll is rotatably carried, aligning means for maintaining alignment of said members 125

comprising relatively movable means at each side of said die and opposite and acting against said members respectively, and a connection across said die and between 5 said relatively movable aligning means for transmitting the motion of one of said relatively movable aligning means to the other.

3. In combination, an annular crushing die having an internal crushing face, a movable and rotatable crushing roll within and eccentric of said die, means for revolving one of said parts, means for supporting said parts, movable non-rotative means at each side of said roll and on which said roll is 10 rotatably carried, aligning means for maintaining alignment of said non-rotative means comprising rocking means at each side of said die mounted on axes at right angles to the axis of said die, and means extending 15 from one to the other side of said die for transmitting the motion of said rocking means from one to the other.

4. In combination, an annular crushing die having an internal crushing face, a movable and rotatable crushing roll within and eccentric of said die and having a peripheral crushing face reciprocal to the inner face of said die, means for revolving one of said parts, means supporting said parts, 20 movable non-rotative means at each side of said roll for rotatively carrying the latter, and relatively movable yielding means at each side of said die for holding said roll outwardly toward said die, relatively movable 25 aligning means connecting said non-rotative means, and movable connecting means across and movable axially of said die connecting said yielding means for transmitting movement of either to the 30 other.

5. In combination, an annular crushing die revolving in an approximate vertical plane and having an internal crushing face, a movable and rotatable crushing roll within and eccentric of said die and having a peripheral crushing face reciprocal to the inner face of said die, means for revolving one of said parts, means for supporting said parts, movable non-rotative means at each 45 side of said roll and by which said roll is rotatably carried, and aligning relatively movable supporting means opposite and acting on and supporting said non-rotative means respectively connected together and reacting from one to the other side of said die for maintaining alignment of said non-rotative means.

6. In combination, an annular crushing die having an internal crushing face, a movable and rotatable crushing roll within and eccentric of said die and having a peripheral crushing face reciprocal to the inner face of said die, means for revolving one of said parts, movable non-rotative means 60 on which said roll is rotatably mounted,

aligning means movable relatively to and controlling movement of said non-rotative means, pressing means inwardly of and acting divergently against said non-rotative means for pressing said roll outwardly toward said die, and a screw extending axially of said die and connecting with said non-rotative means for adjusting said pressing means axially of said die to vary their divergence. 70

7. In combination, an annular crushing die having an internal crushing face, a movable and rotatable crushing roll within and eccentric of said die and having a peripheral crushing face reciprocal to the inner face of said die, means for revolving one of said parts, non-rotative means at each side of said roll and rotatively carrying the latter, relatively movable aligning means connecting said non-rotative means, means for supporting said parts, pressing means at each side of said die inwardly of and acting outwardly against said non-rotative means respectively, and means connecting said oppositely located pressing means axially of said die for adjusting them and transmitting the stress of one to another. 80

8. In combination, an annular crushing die revolving in an approximately vertical plane and having an internal crushing face, a plurality of movable crushing rolls within and eccentric of said die and each having a crushing face reciprocal to the inner face of said die, means for revolving one of said parts, means for supporting said parts, relatively movable non-rotative means at each side of said die on which said rolls are rotatably mounted respectively, pressing means for pressing said rolls outwardly 90 away from one another, relatively movable pivoted aligning means opposite and acting on said non-rotative means respectively, and means connecting said aligning means across said die for maintaining alignment of said non-rotative means at each side of one 100 of said rolls. 105

9. In combination, an annular crushing die revolving in an approximately vertical plane and having an internal crushing face, three movable and rotatable crushing rolls one above the others within and eccentric of said die and each having an internal crushing face reciprocal to the inner face of said die, means for revolving one of said parts, movable non-rotative means on which said rolls are rotatably mounted respectively, pressing means intermediate of and reacting outwardly against said non-rotative means respectively, and yielding means movable relatively to said pressing means and below the axis of said upper roll sustaining said non-rotative means of said upper roll additionally to said pressing means. 115

10. In combination, an annular crushing 120

125

130

die revolving in an approximately vertical plane and having an internal crushing face, a rotatable crushing roll within and eccentric of said die and having a peripheral crushing face reciprocal to the inner face of said die, means for revolving one of said parts, non-rotative means on which said roll is rotatably mounted, and means for supporting said parts comprising a frame 5 having a supporting portion exteriorly of said die, a portion outwardly of and extending past one side of said die, and a tubular portion extending through the interior of said die affording a support for said parts 10 at the other side of said die and affording around such support a space for passage of said die axially over said support, and means affording a cover and mounted on said supporting means for enclosing said 15 die and roll.

11. In combination, an annular crushing die revolving in an approximately vertical plane and having an internal crushing face, a rotatable crushing roll within and eccentric 25 of said die and having a peripheral crushing face reciprocal to the inner face of said die, means for revolving one of said parts, non-rotative means on which said roll is rotatably mounted, and means for supporting 30 said parts comprising a frame mounted exteriorly of said die and having a supporting provision at one side of said die, and having a tubular portion extending through said die having a supporting provision at 35 the other side of and inwardly of the inner diameter of said die affording a space around it through which said die can be passed over said frame, and a cheek piece removably mounted on and removable over 40 said latter supporting portion.

12. In combination, an annular crushing die revolving in an approximately vertical plane and having an internal crushing face, a rotatable crushing roll within and eccentric 45 of said die and having a peripheral crushing face reciprocal to the inner face of said die, means for revolving one of said parts, non-rotative means on which said roll is rotatably mounted, and means for 50 supporting said parts comprising a frame mounted outwardly of said die extending across one side thereof and having a wall covering such side of said die, and having a central tubular portion extending through 55 said die, and having a wall opposite and covering the other side of said die of less size than the internal diameter of said die and over which wall said die can be passed axially.

60 13. In combination, an annular crushing die revolving in an approximately vertical plane and having an internal crushing face, a rotatable crushing roll within and eccentric 65 of said die and having a peripheral crushing face reciprocal to the inner face

of said die, means for revolving one of said parts, non-rotative means on which said roll is rotatably mounted, means for supporting said parts, and means affording a crushing chamber for said die and roll comprising a casing having an apertured wall at one side of said die having an aperture at the side of and larger than said roll and through which the latter can be removed axially, and having a wall at the other side 70 of said die of less size than the internal diameter of said die and affording an annular space around it through which said die may be passed over said latter wall, and having means supporting said latter wall 75 extending through said die and without said latter wall.

14. In combination, an annular crushing die revolving in an approximately vertical plane and having an internal crushing face, 80 a movable and rotatable crushing roll within and eccentric of the upper part of said die and having a peripheral crushing face reciprocal to the inner face of said die, means for revolving one of said parts, movable non-rotative means on which said roll is rotatably mounted, means supporting said parts, upwardly acting rocking means mounted at the side of said roll on an axis 85 at right angles to the axis of said die and acting upwardly on said non-rotative means to resist a crushing pressure from the inner face of said die, and pressing means acting on said rocking means to resist movement 90 of the latter.

15. In combination, an annular crushing die revolving in an approximately vertical plane and having an internal crushing face, a movable and rotatable crushing roll within and eccentric of said die and having a 105 peripheral crushing face reciprocal to the inner face of said die, means for revolving one of said parts, movable non-rotative means on which said roll is rotatably mounted, means for supporting said parts, outwardly acting rocking means pivotally mounted at the side of said die on an axis 110 inwardly of and at right angles to the axis of said roll and acting to hold said non-rotative means outwardly toward the inner face of said die to resist a crushing pressure therefrom, and pressing means acting on said rocking means to resist movement 115 of the latter.

16. In combination, an annular crushing die revolving in an approximately vertical plane and having an internal crushing face, a movable and rotatable crushing roll within and eccentric of said die and having a 120 peripheral crushing face reciprocal to the inner face of said die, means for revolving one of said parts, movable non-rotative means on which said roll is rotatably mounted, means for supporting said parts, outwardly acting pivoted means pivotally 125

- mounted at the side of said die and acting on said non-rotative means to hold said roll outwardly toward the inner face of said die, and a spring reacting in direction substantially parallel with the axis of said die opposite and acting on said pivoted means to resist a pressure from the inner face of said die. 17. In combination, an annular crushing die revolving in an approximately vertical plane and having an internal crushing face, a movable and rotatable crushing roll within and eccentric of said die and having a peripheral crushing face reciprocal to the inner face of said die, means for revolving one of said parts, movable non-rotative means on which said roll is rotatably mounted, means for supporting said parts, pivoted holding means opposite and acting on said non-rotative means at the side of said die for holding said roll outwardly toward the inner face of said die, and a spring within said die acting on said holding means to resist a crushing pressure from the inner face of said die. 18. In combination, an annular crushing die revolving in an approximately vertical plane and having an internal crushing face, a movable and rotatable crushing roll within and eccentric of said die and having a peripheral crushing face reciprocal to the inner face of said die, means for revolving one of said parts, movable non-rotative means on which said roll is rotatably mounted, means for supporting said parts, pivoted holding means opposite and acting on said non-rotative means to resist a pressure from the inner face of said die. 19. In combination, an annular crushing die revolving in an approximately vertical plane and having an internal crushing face, a movable and rotatable crushing roll within and eccentric of said die and having a peripheral crushing face reciprocal to the inner face of said die, means for revolving one of said parts, movable non-rotative means on which said roll is rotatably mounted, means for supporting said parts, pivoted holding means opposite and acting on said non-rotative means to hold said roll outwardly toward the inner face of said die, and a spring acting across said die on said pivoted means to resist a pressure from the inner face of said die. 20. In combination, an annular crushing die revolving in an approximately vertical plane and having an internal crushing face, a movable and rotatable crushing roll within and eccentric of said die and having a peripheral crushing face reciprocal to the inner face of said die, means for revolving one of said parts, movable non-rotative means on which said roll is rotatably mounted, means for supporting said parts, pivoted holding means opposite and acting on said non-rotative means at the side of said die for holding said roll outwardly toward the inner face of said die, and a spring within said die acting on said holding means to resist a crushing pressure from the inner face of said die. 21. In combination, an annular crushing die revolving in an approximately vertical plane and having an internal crushing face, a movable and rotatable crushing roll within and eccentric of said die and having a peripheral crushing face reciprocal to the inner face of said die, means for revolving one of said parts, movable non-rotative means on which said roll is rotatably mounted, means for supporting said parts, pivoted holding means mounted to rock on a pivotal axis and having a portion at one side of such axis opposite and acting on said non-rotative means for holding said roll outwardly toward the inner face of said die, and having a portion at the other side of said axis, and pressing means opposite and acting on said latter portion of said rocking means to resist a crushing pressure from the inner face of said die. 22. In combination, an annular crushing die revolving in an approximately vertical plane and having an internal crushing face, a movable and rotatable crushing roll within and eccentric of said die and having a peripheral crushing face reciprocal to the inner face of said die, means for revolving one of said parts, movable non-rotative means on which said roll is rotatably mounted, means for supporting said parts, pivoted holding means mounted to rock on a pivotal axis and having a portion at one side of said axis opposite and sustaining said non-rotative means for holding said roll outwardly toward the inner face of said die and having a portion at the other side of said axis, adjusting means opposite and engaging said latter portion for adjusting said rocking means, and pressing means acting on said rocking means to resist a crushing pressure from the inner face of said die. 23. In combination, an annular crushing die revolving in an approximately vertical plane and having an internal crushing face, a movable and rotatable crushing roll within and eccentric of said die and having a peripheral crushing face reciprocal to the inner face of said die, means for revolving one of said parts, movable non-rotative means on which said roll is rotatably mounted, means for supporting said parts, pivoted holding means opposite and acting on said non-rotative means at the side of said die for holding said roll outwardly toward the inner face of said die, and a spring within said die acting on said holding means to resist a crushing pressure from the inner face of said die.

ed, means for supporting said parts, rocking holding means mounted to rock on a pivotal axis and having a portion at one side of said axis opposite and holding said non-rotative 5 means and having a portion at the other side of said axis, a spring opposite and acting toward said latter portion to resist a crushing pressure from the inner face of said die, and a screw acting on said spring 10 to adjust its stress toward said latter portion.

24. In combination, an annular crushing die revolving in an approximately vertical plane and having an internal crushing face, 15 a movable and rotatable crushing roll within and eccentric of said die and having a peripheral crushing face reciprocal to the inner face of said die, means for revolving one of said parts, movable non-rotative 20 means on which said roll is rotatably mounted, means for supporting said parts, rocking means mounted to rock on a pivotal axis disposed at right angles to the axis of said roll and having a portion projecting axially of 25 said roll at one side of said axis sustaining said non-rotative means and having a portion projecting radially of said roll at the other side of said axis, and pressing means 30 acting on said latter portion to resist a crushing pressure from the inner face of said die.

25. In combination, an annular revolving die having an internal crushing face, a movable and rotatable crushing roll within and 35 eccentric of said die and having a peripheral crushing face reciprocal to the inner face of said die, means for revolving one of said parts, movable non-rotative means at each side of said roll on which said roll 40 is rotatably mounted, movable aligning means acting on said non-rotative means respectively for aligning them, and motion transmitting means acting on said aligning means and transmitting motion from one to 45 another thereof.

26. In combination, an annular revolving die having an internal crushing face, a movable and rotatable crushing roll within and eccentric of said die and having a peripheral 50 crushing face reciprocal to the inner face of said die, means for revolving one of said parts, movable non-rotative means at each side of said roll on which said roll is rotatably mounted, movable aligning means at 55 each side of said roll acting on said non-rotative means respectively, and motion reversing means connecting said aligning

means for moving one thereof coincidently with the other thereof.

27. In combination, an annular revolving die having an internal crushing face, a movable and rotatable crushing roll within and eccentric of said die and having a peripheral crushing face reciprocal to the inner face of said die, means for revolving one of said parts, movable non-rotative means at each side of said roll on which said roll is rotatably mounted, and fulcrumed means at each side of said roll having at one side of their fulcrum a portion opposite and positioning said non-rotative means, and connected together to move coincidently. 60 65 70

28. In combination, an annular crushing die revolving in an approximately vertical plane and having an internal crushing face, 75 a movable and rotatable crushing roll within and eccentric of said die and having a peripheral crushing face reciprocal to the inner face of said die, means for revolving one of said parts, means for holding said roll outwardly toward the inner face of said die to resist a crushing pressure from the latter, and means for supporting said parts comprising vertically extending portions at 80 one side of said die, and an axial sustaining portion extending through said die and on which said holding means are mounted 85 inwardly of the inner periphery of said die.

29. In combination, an annular crushing die revolving in an approximately vertical 90 plane and having an internal crushing face, a movable and rotatable crushing roll within and eccentric of said die and having a peripheral crushing face reciprocal to the inner face of said die, means for revolving one of said parts, means for holding said roll outwardly toward the inner face of said die to resist a crushing pressure from the latter, pressing means for pressing said roll outwardly toward the inner face of said die, and a support for said parts comprising a vertically extending portion at one 95 side of said die and a sustaining portion extending through said die and in which said pressing means are sustained inwardly of the inner periphery of said die. 100 105

In witness whereof, I have hereunto signed my name in the presence of two subscribing witnesses.

GEORGE HOLT FRASER.
